(57) CLAIM

I claim the ornamental design for shoe upper, as shown and described in the drawings.

DESCRIPTION

FIG. 1 is a shoe upper in accordance with the new design; FIG. 2 is a left side view of the shoe upper shown in FIG. 1;

FIG. 3 is a plan side view of the shoe upper shown in FIG. 1;

FIG. 4 is a frontal side view of the shoe upper shown in FIG. 1; and,

FIG. 5 is a rear side view of the shoe upper shown in FIG. 1.

The broken lines showing the outsole, buckle, and welt are for illustrative purposes only and form no part of the claimed design.
